UNITED STATES PATENT OFFICE

156,775

ANIMATED TRUNDLE TOY

Ervin F. Schultz, Fond du Lac, Wis.

Application April 13, 1948, Serial No. 145,671

Term of patent 3½ years

(Cl. D34—15)

To all whom it may concern:

Be it known that I, Ervin F. Schultz, a citizen of the United States of America, residing at Fond du Lac, in the county of Fond du Lac and State of Wisconsin, have invented a new, original, and ornamental Design for an Animated Trundle Toy, of which the following is a specification, reference being had to the accompanying drawing, forming part thereof.

In the drawings:

Figure 1 is a side elevation of an animated trundle toy, showing my new design the dotted line showing the broken-away handle being for illustrative purposes only, and

Figure 2 is a top plan view of the same.

The dominant features of my new design are shown in solid lines in the drawing.

I claim:

The ornamental design for an animated trundle toy, as shown and described.

ERVIN F. SCHULTZ.
